UNITED STATES PATENT OFFICE.

WESLEY J. BALKWILL, OF ROCHESTER, NEW YORK, ASSIGNOR TO MULTIPOST COMPANY, OF ROCHESTER, NEW YORK, A CORPORATION OF NEW YORK.

PRINTING APPARATUS.

Application filed May 7, 1921. Serial No. 467,516.

To all whom it may concern:

Be it known that I, WESLEY J. BALKWILL, of Rochester, in the county of Monroe and State of New York, have invented certain new and useful Improvements in Printing Apparatus; and I do hereby declare the following to be a full, clear, and exact description of the same, reference being had to the accompanying drawings, forming a part of this specification, and to the reference numerals marked thereon.

This invention has to do with printing apparatus and more especially with printing machines of comparatively small size adapted for printing relatively small work blanks, the chief object of the invention being to provide a simple, practical and efficient machine of the above character capable of rapidly and accurately printing blanks such, for example, as stamps, labels and the like, connected together in the form of a web or strip. Another object is to provide such a machine having means cooperating with the usual lines of weakening or perforations between adjacent blanks of the strip for insuring registry between the printing members and the individual blanks at the printing point. Further objects are to provide a machine of this type having convenient and efficient work holding and managing means. To these and other ends the invention consists in certain improvements and combinations of parts, all as will be hereinafter more fully described, the novel features being pointed out in the claims at the end of the specification.

In the drawings:

Figure 1 is a side elevation of a machine embodying the present invention. Figure 2 is a top plan view of the same. Figure 3 is a view similar to Figure 1 of the opposite side of the machine.

Figure 4 is an elevation of the end of the machine as seen from the right in Figure 1. Figure 5 is an elevation of the opposite end of the machine partly broken away.

Figures 6 and 7 are sectional elevations substantially on the line 6^a—6^a of Figure 2 showing the parts in different operating positions.

Figure 8 is a sectional view substantially on the line 8^a—8^a of Figure 6.

Figures 9 and 10 are sectional views of

a reel for the work taken substantially on lines 9^a—9^a and 10^a—10^a respectively of Figure 1.

Figure 11 is a sectional elevation through the work bed substantially on the line 11^a—11^a of Figure 7.

Figure 12 is a fragmentary elevation of the parts shown at the right hand end of Figure 1 but in different positions.

Figure 13 shows a work blank, such as a stamp, printed by the machine.

Similar reference characters throughout the several views indicate the same parts.

The present embodiment of the invention, which is disclosed herein merely by way of illustration of the principles involved and a preferred practical application thereof, is a machine adapted to be located on a table or similar support for operation by hand or by a small motor for printing work blanks of comparatively small size, as, for example, in pre-cancelling postage stamps. The latter are commonly obtainable in the form of a rolled web or strip with lines of weakening or perforations between adjacent stamps for convenience in separating the same, and the machine is provided with reel means for holding a rolled strip of this character for supplying the same to the machine, and also with means for automatically rewinding the strip after the printing operation. Between the reels the work passes along a bed and between cooperating printing rollers which are rotated to simultaneously print and feed the strip along, the rollers being so constructed as to momentarily release the strip between successive printing impressions. In this application of the machine it is desirable for the printing surfaces to register with the individual stamps so as to make a complete impression on each, and means are therefore provided for engaging and positioning the strip relative to the printing rollers when released by the latter between successive printing impressions, together with devices for preventing inadvertent movement of the work on the bed, or inking the printing surfaces, and other parts, the construction and function of which will more fully appear from a detailed reference to the drawings.

The main supporting frame for the machine comprises side plates 15, Figure 1,

fixed to each other in spaced relation as by bolt means 16. The side plates are provided with feet 17 by which the machine may if desired be secured to a support.

5 Journalled at its ends in the frame plates 15 is a shaft 18 on which is fixed between the plates, Figures 6 to 8 inclusive, a printing roller 19 on the periphery of which are one or more printing means or plates 20, 10 three being shown in the present instance, equally spaced from each other circumferentially of the roller. Between the printing plates the roller is reduced in radius, or cut away, as at 21, to clear or release 15 the work between successive printing impressions. The roller in the present instance is rotated by means of a hand crank 22, Figure 1, on the outer end of shaft 18, and during rotation the printing surfaces de- 20 scribed are brought through an opening 23 in the work bed into printing and feeding engagement with the under side of the work strip, indicated at 24. The work bed, as shown at 25, is preferably a sheet metal 25 plate resting on the top of the frame with flanges engaging the sides of the latter and secured thereto as by screws 26.

On the side of the work opposite the printing roller 19, above the work bed, is 30 a cooperating roller 27 carried on a shaft 28 journalled at its ends in a movable frame 29 having side pieces pivotally supported on a stud shaft 30 mounted on one of the side plates of the frame. Means are pro- 35 vided for rotating roller 27, positively, at the same peripheral speed as the printing roller, comprising a pinion 31 on the shaft of the latter meshing with an idle pinion 32 on the frame which in turn drives a large 40 gear 33 fixed on one end of shaft 30. Meshing with gear 33 is a pinion 34 fixed on shaft 28 of roller 27 to drive the shaft.

The printing surfaces may of course have 45 various forms but it is preferred in the present instance to provide spaced printing bars 35 extending circumferentially of the roller, with the desired printing characters 36 located between the bars 35. These bars serve as effective cancelling marks for the 50 stamps, and the characters 36 show the location of the place of cancellation, as indicated at 35^a and 36^a respectively, in Figure 13. Bars 35 have the additional function of positively feeding the work during the 55 printing impression, in cooperation with the upper roller 27. To this end the latter is preferably formed in three sections, Figure 2, the end ones 37 of which are fixed to the shaft 28, so as to be positively driven, 60 while the intermediate section 38 is freely rotatable on the shaft and is driven by printing characters 36 which will at different times engage different portions of section 38 so as to wear the latter more evenly. 65 It is apparent from the above construction

that as hand crank 22 is rotated rollers 19 and 27 are positively driven and as the printing surfaces 20 of the roller 19 approach the point of tangency of the rollers the latter engage the opposite sides of the 70 work in rolling, printing and feeding contact, the work being alternately released between successive printing engagements by reason of the cut away portions 21 intermediate the printing surfaces. 75

Means are provided for inking the printing surfaces 20 comprising an inking roll 39, Figure 6, rotatably supported by shaft 40 in such position as to apply ink to the surfaces during rotation thereof. Roll 39 80 contacts with a rotating roll 41 on a shaft 42 mounted on a detachable frame 43. The latter is provided with horizontal slots 44 and 45 engaging studs 46 and 47 respectively on the frame, a lever 48 being adjustably supported on a pivot 49 on frame 43 and having a vertically extending slot for engagement with stud 47 to detachably secure the frame in place. Roll 41 dips into ink in a reservoir 50 on frame 43 so that 90 an adequate supply of ink for the printing surfaces is constantly maintained. 95

In order to restrain the work against inadvertent movement on the bed there is provided a cross bar 51 on frame 29 preferably 100 integral with the side pieces of the latter. Fixed in the cross bar 51 are vertical bearing sleeves 52 and 53 in which are slidably carried spindles 54 and 55, respectively, fixed at their lower ends to a presser foot 105 or plate 56 arranged to bear against the upper side of the work. Springs 57 coiled about sleeves 52 and 53 serve to yieldably press the plate against the work, spindle 55 having at its upper end a screw 58 the head of which limits the movement of the spindles in their sleeves when frame 29 is moved away from the work bed, as will be presently explained. The work bed is provided with upturned lugs or flanges 59, Figure 110 11, forming a channel in which the work is guided and held by the presser foot. Frame 29 carries at its right hand end, Figure 6, a cross rod 60 on which are pivotally supported the side arms of a bail 61, 115 Figure 1, straddling frame 29. The arms are provided at their lower ends with slots 62 for detachable engagement with studs 63 on the main frame for holding frame 29 in operating position with roller 27 against the 120 work. By means of a handle 64 on bail 61, however, the latter may be rocked to disengage studs 63 after which frame 29 may be moved about shaft 30 to the elevated position indicated in Figure 12, in which position roller 27 and presser foot 26 are moved clear of the work bed so that the latter is 125 left exposed for the convenient insertion and removal of the work.

Means are provided for holding the piv- 130

oted frame 29 in elevated position comprising a recess 65 formed in the circular end of one of the side pieces of frame 29 adjacent its pivotal support 30. Engaging this 5 end of the side piece is the curved end 66 of an arm 67 having a longitudinal slot 68 embracing a pair of studs 69 on the main frame so that the arm is movable toward and from the end of the side piece of frame 10 29. A spring 70 fixed to one of the studs 69 and to arm 67 urges the latter toward the frame side piece and when the frame is raised its recessed portion 65 is engaged by the end of arm 67 and the frame is thus 15 yieldably retained in elevated position.

The work may be supplied to the printing members and disposed of after being printed in various ways. In the present instance it is preferred to provide means on the 20 main frame for holding the work and supplying the same to the rollers comprising a reel or spool 71 rotating freely on a shaft 72 mounted on one end of the main frame. From this reel the work is led along the 25 printing bed under the presser foot 56 and between the printing rollers to the other end of the work bed where there is preferably provided a second reel or spool 73 rotated automatically for rewinding the 30 printed work. This reel is in the present instance supported on a shaft 74, Figure 9, which is rotatably carried in an elongated bearing 75 fixed on the main frame and rotated by means described hereafter. Since 35 this reel in the present embodiment is merely for winding up the work as the latter is fed through the machine by the printing rollers or by other means described hereafter, there is preferably provided for 40 it a yieldable driving connection transmitting a force sufficient only for winding up the work as fed to the reel. To this end the reel is rotatably carried on shaft 74 and the inner flange 76 of the reel is provided with a series of openings 77 or other 45 engaging means with which cooperates the curved end of a spring finger 78 extending through an opening 79 in and carried by a flange 80 fixed on shaft 74. From this construction it is apparent that as the shaft is 50 rotated by means presently to be described the reel is yieldably driven by engagement of the finger 78 with the apertured flange 77. This reel, as also the work supplying 55 reel 71, preferably have their outer flanges removably carried in any suitable manner, for convenience in the application and detachment of the work. In this construction, 60 which is the same for both reels 71 and 73, the outer flange of reel 73 is fixed on a hub 81 rotatable and longitudinally slidable on the reduced outer end of the shank of the reel or of the shaft 74. The hub is provided with a radially extending bore 65 83 in which is carried a spring pressed ball

84 yieldably engaging in a circular groove 85 in the extension 82, by means of which construction the outer reel flange may be readily removed and replaced when removing and replacing the work. The shank 70 of reel 73 is provided with a slot 85^a or other means for attaching the end of the work strip thereto. The means for driving shaft 74 and reel 73 comprises a pinion 86 fixed on the shaft and meshing with the 75 gear 33.

As already stated, it is desired to have the printing impressions register with the individual stamps to insure a complete impression on each. It may not be feasible, 80 however, to adjust the strip when inserting it in the machine so that the first stamp to be printed registers with the printing rollers properly for this result. Nor has it been found satisfactory to rely upon the 85 feeding action of the printing rollers alone to advance the strip at each impression a distance equal to the width of a stamp in the direction of feeding movement, as this feeding action may vary with the speed of 90 operation and other considerations. It is preferred therefore to so dimension the printing means as to advance the work at each impression a distance somewhat less than the width of a stamp and to provide 95 means for positioning the work relative to the printing rollers each time it is released by the latter between successive impressions. This means or positioning device 100 comprises preferably one or more reciprocating, pointed fingers 88, Figures 7 and 11, projecting upwardly through an opening 87 in the work bed and yieldably supported so as to bear against the under side of the 105 work for engagement with the lines of 110 weakening or perforations between adjacent stamps. A plurality of such fingers are employed in the present instance, located opposite the presser foot 56 where the work is constrained to its proper path of movement, and the presser foot is slightly recessed as at 89 to permit the fingers to fully engage with the perforations between adjacent stamps. Fingers 88 are pivotally supported on a spindle 90 mounted in spaced ears 91 on opposite sides of a reciprocating carriage 92 having at each side a pair of rollers 93, Figure 1, working in slots 94 in the side plates 15 of the main frame. Each finger 88 has a slot loosely embracing 115 a second spindle 95 carried by ears 91 so that it has a limited pivotal movement toward and from the work, being yieldably moved to bear against the latter by means of a spring 97 on the carriage and engaging each 120 finger.

As the positioning device operates upon the work when the latter is released by the printing rollers to position the same before each engagement thereof by the printing 130

surfaces, there are provided means for effecting a reciprocating movement of the positioning device in timed coordination with the rotation of the printing roller 19. This coordination connection comprises a pair of plates 98 one on each side of carriage 92 and movably connected with the latter by being pivotally supported on the spindle of one of the rollers 93. Plates 98 extend past the 10 ends of the printing roller and are pivotally connected to arms 99 which in turn are pivotally supported on a cross shaft 100 carried by the main frame. One of the arms 99 carries a roller or follower 101 held in contact with an end of the printing roller at one side of the printing surfaces thereon, Figure 8, by means of a spring 102 fixed to one of the plates 98 and the main frame. This 15 end of the printing roller is provided with projecting portions 103 having substantially the shape of the printing bars 35 and with similar intermediate cut away portions. Roller 101 thus engages with a cam like surface on the printing roller so shaped as to reciprocate the positioning device so that, just prior to each printing engagement of the work, the fingers 88 are moved toward the left, Figure 6, and their ends engage the 20 lines of weakening or perforations in the work strip and move the latter past the presser foot 56 and relative to the printing rollers. The latter thus always engage a stamp or work piece in the desired spaced relation to the margins of the latter, or in 25 other words, so that a complete printing impression is made approximately centrally of each stamp.

The operation of the machine has been indicated in connection with the above description 40 of its construction. To apply a rolled strip of stamps to the machine, frame 29 is released and raised by means of handle 64 so as to clear the work bed. The outer end of reel 71 is removed and the rolled strip placed on the shank of the reel after which the outer flange of the latter is replaced. The end of the strip is carried along the work bed to its other end and engaged in the slot 85^a of the shank of the opposite reel 45 73. Rocking frame 29 is then lowered and secured in position and the machine is ready for operation. Rotation of shank 22 produces a preliminary reciprocation of fingers 88 which slide over the under side of the work into engagement with a line of perforations into which they enter so as to advance and position the work between the printing roller. When one of the printing 50 surfaces of the latter reaches the printing point the work is thus properly positioned for an impression. The rollers simultaneously print and feed the work, printing the latter as indicated in Figure 13, after which the work is momentarily released and again 55 positioned if necessary by the reciprocating 60 65

fingers. The printing impressions and the alternate positioning action of fingers 88 thus occur in proper sequence and the work is accomplished accurately and rapidly. The driving connection with the winding 70 reel 73 transmits a force sufficient only for winding up the work fed to it by the printing rollers and insufficient to move the work under the presser foot so that the feeding of the work is controlled alone by the printing members and a positioning device. When the roll has been printed and transferred to reel 73, the outer end of the latter may be removed and the roll detached for use. As 75 apparent from the drawings the machine is compact and self contained in character and the construction employed is simple and practical in form. The various parts are convenient to manipulate so that the work may be quickly applied to the machine and 80 expeditiously and accurately printed. 85

I claim as my invention:

1. A printing apparatus comprising a pair of rollers rotatably supported on opposite sides of the work and adapted during rotation to alternately engage and release the work to intermittently print and feed the same, work holding means for supplying work to said rollers, guide means yieldably restraining movement of the work between said work holding means and rollers, a positioning device movably supported for engagement with the work adjacent said guide means and for moving the work past the latter and positioning the same relative to said rollers, reel means for winding up the work discharged from said rollers, and actuating means for effecting coordinated movement of said rollers and positioning device and for rotating said reel means. 100 105

2. An apparatus comprising a pair of movable members adapted for intermittent feeding engagement with opposite sides of the work, one of said members having means for printing the work during said feeding engagement therewith, work holding means for supplying work to said members, means between said work holding means and rollers for yieldably restraining movement of the work, a movable positioning device cooperating with said restraining means for moving the work past the latter and for positioning the work relative to said members between engagements of the latter therewith, reel means for rewinding the printed work, and actuating means including a movement coordinating connection between said positioning device and members for actuating the latter and also said reel means. 110 115 120

3. An apparatus comprising a pair of movable members adapted for intermittent feeding engagement with opposite sides of the work, one of said members having means for printing the work during said feeding engagement therewith, reel means for supply- 125 130

ing work to said members, a movable positioning device located between said work supplying means and members for positioning the work relative to said members between engagements of the latter therewith, guide means yieldably resisting movement of the work adjacent said positioning device, reel means for rewinding the printed work, and actuating means for said members, position

10 sitioning device and rewinding reel including a yieldable driving connection for the latter and a movement coordinating connection between said members and positioning device.

15 4. A printing apparatus comprising a pair of rollers rotatably supported for engagement with opposite sides of the work to simultaneously print and feed the same, one of said rollers having its periphery provided 20 with printing means at one part and cut away at another part to effect alternate engagement and release of the work, a pair of devices in engagement with opposite sides of the work and one movable relatively to the 25 other to move the work and position the same relative to said rollers when released by the latter, and actuating means for said rollers and positioning device including a movement coordinating connection therebe- 30 tween.

35 5. A printing apparatus comprising a pair of rollers rotatably supported for engagement with opposite sides of the work to simultaneously print and feed the same, one of said rollers having its periphery provided 40 with printing means at one part and cut away at another part to effect alternate engagement and release of the work, work holding means for supplying the work to said rollers, a stationary presser foot engaging the work, reel means for winding the printed work, a positioning device for movement in engagement with a portion of the work supported by said presser foot to move 45 the work past said presser foot and to position the same relative to said rollers when released by the latter, and means for actuating said rollers and device in coordination with each other and for rotating said reel 50 means.

55 6. A printing apparatus comprising a pair of rollers rotatably supported for engagement with opposite sides of the work to simultaneously print and feed the same, one of said rollers having its periphery provided 60 with printing means at one part and cut away at another part to effect alternate engagement and release of the work, work holding means for supplying the work to said rollers, reel means for winding the printed work, stationary means for restraining movement of the work located between said rollers and work holding means, a positioning device for engagement with a portion 65 of the work supported by said restrain-

ing means for moving the work past said restraining means to position the same relative to said rollers when released by the latter, and actuating means including a yieldable driving connection with said reel 70 means and a coordinating connection between said rollers and positioning device for operating the latter in timed relation with each other.

7. A printing apparatus comprising a pair of members movable into intermittent engagement with opposite sides of the work to simultaneously print and feed and subsequently release the same, stationary means for restraining movement of the work located on one side of said members, reel means on the other side of said members for winding up the printed work, a positioning device for engagement with a portion of the work supported by said restraining means for moving the work past said restraining means to position the same relative to said members when released by the latter, and actuating means including a yieldable driving connection with said reel means and a 80 coordinating connection between said members and positioning device for operating the latter in timed relation with each other.

8. A printing apparatus comprising a pair of members movable into intermittent engagement with opposite sides of the work to simultaneously print and feed and subsequently release the same, a stationary presser plate engaging one side of the work in advance of said members, a movable positioning finger engaging the side of the work opposite said plate for positioning the work relative to said members when released by the latter, reel means for winding up the printed work, and actuating means including a yieldable driving connection with said reel means and a coordinating connection between said members and finger for operating the latter in timed relation with each other.

9. A printing apparatus comprising a pair of members movable into intermittent engagement with opposite sides of the work to simultaneously print and feed and subsequently release the same, a stationary presser plate engaging one side of the work in advance of said members, a reciprocating positioning finger engaging the work opposite said plate for positioning the work relative to said members when released by the latter, reel means for supplying work to said parts, reel means for winding the printed work, and actuating means for yieldably rotating said winding means and moving said members and finger in timed relation with each other.

10. A printing apparatus comprising a pair of rollers rotatably supported for engagement with opposite sides of the work to simultaneously print and feed the same,

one of said rollers having its periphery provided with printing means at one part and cutaway at another part to effect alternate engagement and release of the work, a stationary presser plate bearing on the work in advance of said rollers, a reciprocating finger bearing on the work opposite said plate for positioning the work relative to said rollers when released by the latter, and 10 actuating means for rotating said rollers and reciprocating said finger in timed coordination with each other.

11. A printing apparatus comprising a pair of rollers rotatably supported for engagement with opposite sides of the work to simultaneously print and feed the same, one of said rollers having its periphery provided with printing means at one part and cut way at another part to effect alternate 20 engagement and release of the work, a presser plate bearing on the work in advance of said rollers, means supporting said plate for movement to and from operative position, a plurality of fingers reciprocating 25 in yieldable engagement the work opposite said plate to position the work relative to said rollers when released by the latter, and actuating means for rotating said rollers and reciprocating said fingers.

12. A printing apparatus comprising a pair of rollers rotatably supported for engagement with opposite sides of the work to simultaneously print and feed the same, one of said rollers having its periphery provided with printing means at one part and 30 cut away at another part to effect alternate engagement and release of the work, a presser plate bearing on the work in advance of said rollers, means supporting said plate for movement to and from operative position, a plurality of fingers reciprocating 35 in yieldable engagement the work opposite said plate to position the work relative to said rollers when released by the latter, and actuating means including a yieldable driving connection with said reel means and a coordinating connection between the printing roller and positioning fingers for moving the latter in timed relation with each other.

13. A printing apparatus comprising a pair of rollers rotatably supported for rolling, printing and feeding engagement with 55 opposite sides of the work with a portion of one of said rollers reduced in radius to release the work between successive printing engagements therewith, a frame movable to and from operative position for supporting 60 one of said rollers and also a means for restraining movement of the work, a positioning device for moving the work past said restraining means to position the work relative to said rollers when released by the

latter, and actuating means for rotating 65 said rollers and operating said positioning device in coordination with each other.

14. A printing apparatus comprising a pair of rollers rotatably supported for rolling, printing and feeding engagement with 70 opposite sides of the work with a portion of one of said rollers reduced in radius to release the work between successive printing engagements therewith, a device for engagement with one side of the work to restrain movement thereof, a device for engagement with the side of the work opposite said restraining device to move the work past the latter and position it relative to said rollers when released thereby, a movable frame carrying one of said rollers and one of said devices, said frame being movable to and from operative position to expose the work, and actuating means for rotating said rollers and operating said positioning device in coordination with each other.

15. A printing apparatus comprising a pair of rollers rotatably supported for rolling, printing and feeding engagement with 75 opposite sides of the work with a portion of one of said rollers reduced in radius to release the work between successive printing engagements therewith, a device for restraining movement of the work, a device 80 for moving the work to position the same relative to said rollers when released thereby, a frame carrying one of said rollers and also one of said devices and movable to and from operative position to expose 85 the work, reel means for winding the printed work, and actuating means for rotating said rollers and operating said positioning device in coordination, including a yieldable driving connection with said reel 90 means.

16. A printing apparatus comprising a pair of rollers rotatably supported for rolling, printing and feeding engagement with 95 opposite sides of the work with a portion of one of said rollers reduced in radius to release the work between successive printing engagements therewith, a presser plate for yieldably restraining movement of the work, a reciprocating finger for moving the 100 work to position the same relative to said rollers when released by the latter, a frame carrying said plate and one of said rollers and movable to and from operative position to expose the work, a reel for winding the 105 printed work, and actuating means for operating said rollers and positioning device in coordination and for yieldably rotating said reel.

17. An apparatus comprising a pair of 110 rollers rotatably supported for rolling, printing and feeding engagement with opposite sides of the work, one of said rollers

- having a plurality of printing means spaced about its periphery with the latter cut away between said printing means to release the work between successive impressions, a 5 movable positioning device engaging the work to position the same relative to said rollers when released by the latter, a stationary foot supporting the work opposite said device actuating means for rotating 10 said rollers and parts actuated thereby for moving said positioning device between successive printing impressions.
18. A printing apparatus comprising a pair of rollers rotatably supported for rolling, printing and feeding engagement with opposite sides of the work with a portion of one of said rollers reduced in radius to release the work between successive printing engagements therewith, a movable positioning device engaging the work to position the same relative to said rollers when released thereby a stationary resilient presser foot supporting the work opposite said device, actuating means for rotating said rollers, a cam driven by said actuating means, a follower for said cam, and parts connected with said follower for moving said positioning device in coordination with said rollers.
19. An apparatus comprising a work bed, a pair of rollers supported for rolling engagement with opposite sides of the work on said bed, one of said rollers having relatively high and low portions for alternate feeding engagement with and release of the work, a reciprocating finger yieldably engaging the work on said bed, a foot supporting the work at the point of engagement thereof by said finger, actuating means for rotating said rollers, mechanism including cam means rotatable with said rollers for reciprocating said finger to position said work relative to said rollers when released thereby, a reel for winding the printed work, and a yieldable driving connection between said actuating means and reel.
20. An apparatus comprising a work bed, a roller rotatably supported for engagement with one side of the work on said bed and having a high portion provided with printing means and also a low portion for printing and feeding the work and alternately releasing the same, a frame pivotally supported for movement toward and from said bed, a shaft on said frame, a roller on said shaft for cooperating engagement with the work opposite said printing roller, means on said frame restraining movement of the work on said bed, a movable positioning device engaging the work to position the same relative to said rollers when released by the latter, a pinion on said roller shaft, a gear concentric with the pivot of said frame and meshing with said pinion, and actuating
- means for rotating said printing roller and gear including a connection with said positioning device to move the latter in coordination with said printing roller.
21. An apparatus comprising a work bed, a roller rotatably supported for engagement with one side of the work on said bed having a high portion and a low portion, work feeding means and printing means on said high portion, a shaft, a roller on said shaft for engagement with the opposite side of the work including a section fixed on said shaft for cooperation with said work feeding means and a section rotatable on said shaft for cooperation with said printing means, actuating means for rotating the printing roller and shaft to print and feed and alternately release the work, means yieldably restraining movement of the work on said bed, a device for positioning the work relative to said printing roller when released thereby, and a connection between said actuating means and positioning device for moving the latter in coordination with said printing roller.
22. An apparatus for printing successive sections of a paper strip formed by uniformly spaced transversely extending weakened lines, comprising a pair of rollers rotatably supported for printing and feeding engagement with opposite sides of the strip sections, one of said rollers having a low portion to release the strip between successive printing engagements therewith, means for guiding and yieldably restraining movement of the strip, a plurality of reciprocating fingers bearing against the strip for engagement with the weakened lines thereof to position the sections relative to said rollers when released by the latter, a reel for supplying the strip to be printed, a second reel for winding the printed strip, and actuating means for said rollers having a yieldable driving connection with said second reel and a connection with said fingers to move the same in coordination with said rollers.
23. In a printing apparatus for making successive impressions on a web in predetermined relation to spaced points thereof, the combination of printing members, a device comprising means for supporting and tensioning the web in advance of said members and means adapted for actuating engagement with the web opposite said supporting means and at said spaced points thereof exclusively and movable to move and position the web between impressions with said points in predetermined relation to said members, and means for actuating said members and device in timed coordination.
24. An apparatus for printing successive sections of a paper strip formed by uniformly spaced transversely extending weakened lines, comprising a pair of rollers rotat-

ably supported for printing and feeding engagement with opposite sides of the strip sections, one of said rollers having a low portion to release the strip between successive printing engagements therewith, means for supporting and tensioning said web, a device adapted for actuating engagement with the web adjacent said supporting means and at

said weakened lines thereof exclusively and movable to effect additional movement of the web for positioning the same between impressions with said weakened lines in predetermined relation to said rollers, and means for actuating said rollers and device in timed coordination.
